UNITED STATES PATENT OFFICE.

ROLLO ROBIN BELL, OF LOS BANOS, CALIFORNIA.

INTERNAL-COMBUSTION MOTOR.

1,216,400.

Specification of Letters Patent. Patented Feb. 20, 1917.

Application filed September 21, 1915. Serial No. 51,851.

To all whom it may concern:

Be it known that I, ROLLO R. BELL, a citizen of the United States, residing at Los Banos, in the county of Merced and State of California, have invented a new and useful Internal-Combustion Motor, of which the following is a specification.

The device forming the subject matter of this application is an internal combustion engine and the invention aims to provide novel means for admitting an explosive charge between a pair of pistons mounted to move in opposite directions, and to provide novel means for firing the charge and exhausting the same.

It is within the province of the disclosure to improve generally and to enhance the utility of devices of that type to which the present invention appertains.

With the above and other objects in view which will appear as the description proceeds, the invention resides in the combination and arrangement of parts and in the details of construction hereinafter described and claimed it being understood that changes in the precise embodiment of the invention herein disclosed can be made within the scope of what is claimed, without departing from the spirit of the invention.

In the accompanying drawings:

Figures 1 and 2 are longitudinal sections embodying an internal combustion engine constructed in accordance with the present invention, the pistons being in different positions;

Fig. 3 is a vertical longitudinal section, the cutting plane being passed through the structure at right angles to the cutting planes in Figs. 1 and 2;

Fig. 4 is a side elevation of the engine.

In the drawings, the numeral 1 has been employed to designate generally a crank case provided with guides 2. Journaled for rotation in the crank case 1 is a shaft 3 equipped with cranks 4 and 5.

The crank case 1 carries a cylinder 6 embodying a head 7, the cylinder being suitably water-jacketed as shown at 8. In the cylinder 6 adjacent its top is an inlet port 9 communicating with a supply pipe 10. Any

suitable means, such as a common shaft actuated puppet valve may be employed for controlling the port 9, this detail having been omitted from the drawings because it is well understood, and because, in general, an engine construction cannot be characterized patentably by any specific firing or charge controlling means. Intermediate its ends, the cylinder 6 is supplied with one or more spark plugs 11. The cylinder 6 is provided, in its inner face and adjacent its top with upright, longitudinal channels 12. Below the channels 12, the cylinder 6 is furnished with a lateral, annular inlet passage 14. Below the passage 14, the cylinder 6 carries an annular exhaust passage 15 communicating with an exhaust pipe 16, the passage 15 opening into the interior of the cylinder 6 as shown at 17.

Mounted to reciprocate in the cylinder 6 is an outer piston 18 provided with a firing port 20 adapted to coincide with the spark plugs 11, the piston comprising a head 19. Adjacent its lower end, the outer piston 18 carries a shaft 21, a pitman 23 forming an operative connection between the shaft and the crank 4. In the outer face of the outer piston 18, longitudinal channels 23 are formed, the same terminating in spaced relation to the ends of the piston, the piston being provided with combined inlet and exhaust ports 24.

Mounted to reciprocate within the outer piston 18 is an inner piston 25 embodying a head 26, the inner piston preferably comprising laterally separable parts united by bolts or otherwise, as shown best at 27 in Fig. 3. In the inner piston 25 there is an elongated opening 28 in which the shaft 21 of the piston 18 is adapted to move, said piston being provided at its lower end with a cross head 29 carrying shoes 30, adapted to coact with the guides 2, the shoes being adjustably secured to the cross head 29, as indicated at 31. A pitman 32 forms an operative connection between the cross head 29 and the crank 5.

The space between the head 19 of the outer piston and the head 7 of the cylinder 6 constitutes a compression chamber 33, the space

between the head of the outer piston and the head 26 of the inner piston constituting a compression chamber 34.

In practical operation, presupposing that the parts are disposed as shown in Fig. 3 of the drawings, a charge has been compressed in the chamber 33 and has flowed by way of the channels 12 in the cylinder 6 and by way of the channels 23 in the outer piston 18 into the inlet passage 14. When the parts are thus arranged, the outlet ports 24 of the cylinder 18 are in registration with the openings 17 in the exhaust passages 15. The outer piston 18 then moves upwardly, to a position slightly above the position shown in Fig. 3, whereupon, for an instant, the inlet passage 14 is in communication with the ports 24, and at the same time, the ports 24 are in communication with the exhaust passage 15. During this short interval of time, a new charge is projected upwardly into the explosion chamber 34 in the piston 18 and scours out the exploded charge through the port 24 and the passage 15, it being observed that the lower portion of the inlet passage 14 is properly shaped to produce this result. The parts then assume the position shown in Fig. 1, the ports 24 in the piston 18 moving into full registration with the inlet passage 14, the compressed gas in the passage 14 entering the compression chamber 34 of the piston 18.

Subsequently, the pistons 18 and 25 move toward each other into the positions shown in Fig. 2, whereupon the firing port 20 is brought into registration with the spark plugs 11 and the compressed charge is exploded.

The spark plugs 11 and the firing port 20 are not insisted upon as necessary elements, since other firing mechanisms may be supplied, without jeopardizing the utility of the invention.

Having thus described the invention, what is claimed is:—

1. In an internal combustion engine, a cylinder; an outer piston working in the cylinder; an inner piston working in the outer piston, the space between the heads of the pistons constituting an explosion chamber, and the space between the head of the outer piston and the cylinder head constituting a compression chamber, the cylinder having a pocket and being provided with an exhaust outlet, the outer piston being provided with a port at times establishing a communication between the pocket, the exhaust outlet and the explosion chamber, the adjacent faces of the outer piston and the cylinder being provided with communicating channels establishing a communication between the compression chamber and the pocket.

2. In an internal combustion engine, a cylinder; an outer piston working in the cylinder; an inner piston working in the outer piston; the space between the end of the outer piston and the cylinder constituting a compression chamber, and the space between the ends of the pistons constituting an explosion chamber; the cylinder having a pocket and an exhaust outlet, the outer piston having a port, the cylinder and the outer piston having passages establishing communication between the compression chamber and the pocket when the port is out of registration with the pocket, the outer piston being movable to dispose the port in registration with the pocket and the exhaust outlet, the pocket being shaped to project the charge into the explosion chamber to effect a scouring thereof, the outer piston being movable to dispose the port in full registration with the pocket and out of registration with the exhaust port; and means for connecting the pistons for simultaneous movement in opposite directions.

3. In an internal combustion engine, a cylinder; an outer piston mounted to reciprocate in the cylinder; an inner piston mounted to reciprocate in the outer piston, the space between the end of the outer piston and the head of the cylinder constituting a compression chamber, the space between the ends of the pistons constituting an explosion chamber; means for connecting the pistons for simultaneous movement in opposite directions; the cylinder having an exhaust outlet and being provided with a lateral inlet pocket, the cylinder being provided in its inner face with a longitudinal passage opening into the compression chamber, the outer piston being provided in its outer face with a longitudinal passage and having a port; the longitudinal passages coacting to establish communication between the compression chamber and the pocket when the port is out of registration with the pocket, the outer piston being movable to dispose the port into registration with both the pocket and the exhaust outlet and the pocket being shaped to project the charge into the explosion chamber to effect a scouring thereof, and the piston being movable to dispose the port into full registration with the pocket and out of registration with the exhaust outlet.

4. In an internal combustion engine, a cylinder provided with a circumscribing pocket, the lower wall of which is upwardly inclined to form a deflector, the cylinder having an exhaust port; an outer piston working in the cylinder; an inner piston working in the outer piston, the space between the heads of the pistons constituting an explosion chamber, the space between

the head of the outer piston and the head of the cylinder constituting a compression chamber, the outer piston having a port which at times co-operates with the deflector portion of the pocket, and at times communicates with the exhaust port, the adjacent faces of the outer piston and the cylinder being provided with communicating channels permitting a transfer of fuel

from the compression chamber to the explosion chamber by way of the pocket.

In testimony that I claim the foregoing as my own, I have hereto affixed my signature in the presence of two witnesses.

ROLLO ROBIN BELL.
